UNITED STATES PATENT OFFICE.

HORACE SEE, OF POTTSVILLE, PENNSYLVANIA.

IMPROVEMENT IN VALVE-GEAR OF PUMPING-ENGINES.

Specification forming part of Letters Patent No. 117,570, dated August 1, 1871.

To all whom it may concern:

Be it known that I, HORACE SEE, of Pottsville, in the county of Schuylkill and State of Pennsylvania, have invented certain Improvements in the Valve-Gear of Pumping-Engines, of which the following is a specification:

My invention applies to that class of engines which employs a rod moving coincident with the piston to operate the valve-gear; and relates: First, to the combination of the tappet-arms, rock-shafts, and valve-rods, in such a manner that the latter make a direct connection between the valve-stems and rock-shafts. Second, to the combination of the tappet-arm, quadrant, and dash-pot arm in one piece. Third, to the combination of the quadrant and dash-pot arm in one piece.

Fig. 1 is a front view of a vertical, single-acting, non-condensing engine, to which my invention is applied, with a portion of the plug-rod broken away. Fig. 2 is a plan of the same. Fig. 3 is a side view looking in the direction of the arrow 1 with the dash-pots in section. Fig. 4 is a detached side view of the valve-gear looking in the direction of the arrow 2. Fig. 5 is a detached sectional side view of the valve-gear looking in the direction of the arrow 1. Fig. 6 is a front view of the valve-gear applied to a vertical, single-acting, condensing-engine, with the plug-rod removed; also, the bearing-caps taken off. Fig. 7 is a detached sectional side view of the same, looking in the direction of the arrow 3.

A is the steam-cylinder resting on and secured to the girders P and P' for connecting it with the foundation. B is the steam-chest connected to and communicating with the bottom of the cylinder A by the pipe O; also, communicating with the top through the pipe N. Steam is admitted to the chest through the nozzle f, and exhausted through g. C is a piston-rod extending above, through a stuffing-box, into the cylinder A, and secured to a piston which has not been shown. D is a cross-head with an extension below for operating the pump. The plug-rod E for operating the valves is worked from this cross-head and guided on the steam-chest B. F is a stem connected to the steam-valve, and G one connected to the exhaust. Neither of these valves is shown, as there is nothing novel in their construction. H is the steam, and I the exhaust-tappet, both being secured to the plug-rod E. F² is the steam, and G² the exhaust rock-shaft. F³

is the steam, and G³ the exhaust tappet-arm, with a handle on one side and at the end of each for working by hand. These are, respectively, secured to the rock-shafts F² and G². The arm F³ has the quadrant F⁴ incorporated with it. G⁴ is the exhaust-quadrant, secured to the rock-shaft G². M and M' are bearings carrying the rock-shafts F² and G², and secured to the pipe N. F¹ is a rod connecting the valve-stem F with the rock-shaft F². The rod G¹ also connects the stem G with the rock-shaft G², the connection of these rods with the shafts being made by pins placed out of center on an enlargement at one end. K is the steam, and L the exhaust dash-pot plunger, working, respectively, in the pots K' and L', which are joined together and secured to the pipe N. The plunger K is connected to the arm F³ by the rod k, and the plunger L to the quadrant G⁴ by the rod l, the pins for making the connection being placed out far enough to obtain the necessary leverage. The drawing represents the piston and plug-rods as moving up, the steam-valve being open and the exhaust closed. The double-beat Cornish valve, on account of its being very nearly balanced, is generally used. The steam-valve is kept open by the weight of the dash-pot plunger K. The weight of the dash-pot plunger L is prevented from opening the exhaust-valve by the steam-quadrant F⁴ holding the exhaust-quadrant G⁴. The steam-tappet H will, by the plug-rod E moving up, strike the steam-tappet arm F³, turning the rock-shaft F², which will close the steam-valve through the rod F¹ and stem F; also, moving the steam-quadrant F⁴ clear of the exhaust-quadrant G⁴. The exhaust-quadrant G⁴, now being free, is moved by the weight of the dash-pot plunger L, turning, at the same time, the rock-shaft G², which opens the exhaust-valve through the rod G¹ and stem G; also, throwing up the exhaust tappet-arm G³. The exhaust-valve being open, the rods C and E will descend, and before the end of the stroke the tappet I will strike the arm G³, turning, at the same time, the shaft G², which will close the valve through the rod G¹ and stem G; also, move the quadrant G⁴ clear of the quadrant F⁴, and allow the plunger K to depress the arm F³, turning the rock-shaft F² and raising the rod F¹ with the stem F attached, opening by this operation the steam-valve. The piston will again ascend, from which will follow the same movements. It may be more convenient in the man-

ufacture to make the quadrant F^4 solid with the rock-shaft F^2 and afterward join the arm to them; also, to make the quadrant G^4 solid with the rock-shaft G^2 . Figs. 6 and 7 show my invention applied to a condensing-engine, where the steam, exhaust, and equilibrium-valves are in one chest. Q is the equilibrium valve-stem, which is attached to a valve that allows the steam, after the piston has completed the up-stroke, to pass around to the top of the piston. Q^1 is the equilibrium valve-rod connecting the stem Q with a projection on the tappet-arm Q^3 . Q^2 is the equilibrium rock-shaft. Q^6 is an arm on one end of the shaft Q^2 , and connected by the rod r with the equilibrium dash-pot plunger. Q^5 is a handle incorporated with the arm Q^6 for working the equilibrium-valve by hand. Q^4 is the equilibrium-quadrant, which works with the exhaust quadrant and is secured to the shaft Q^2 . The exhaust tappet-arm and quadrant are in one piece. No quadrant is used on the steam-shaft F^2 , the opening of the steam as well as the exhaust-valve being regulated by a cataract, which, on account of its being well known; has not been shown. The

exhaust-valve is closed by the plug-rod near the end of its up-stroke. At the same time, the equilibrium-quadrant Q^4 being freed, the weight of the dash-pot plunger opens the equilibrium-valve. The equilibrium-valve is closed by a tappet on the back of the plug-rod during its down-stroke striking the arm Q^3 .

In the figures the steam and exhaust-valves are supposed to be open and the equilibrium closed.

I do not claim the use of the tappet-arms, quadrants, rock-shafts, or dash-pot arms separately.

I claim as my invention—

1. The combination of the tappet-arm, rock-shaft, and valve-rod, substantially as and for the purpose hereinbefore set forth.

2. The combination of the tappet-arm, quadrant, and dash-pot arm, substantially as set forth.

3. The combination of the quadrant and dash-pot arm, substantially as set forth.

HORACE SEE.
